DESIGN FOR A CUSHION CAP FOR CASH REGISTER CONTROL KEYS

Garry W. Munson, East Orange, N. J.

Application November 25, 1938, Serial No. 81,353

Term of patent 7 years

To all whom it may concern:

Be it known that I, Garry W. Munson, a citizen of the United States and resident of East Orange, county of Essex, and State of New Jersey, have invented a new, original, and ornamental Design for a Cushion Cap for Cash Register Control Keys, of which the following is a specification, reference being had to the accompanying drawing, forming a part thereof.

Fig. 1 represents a top plan view of a cushion cap for cash register control keys showing my new design;

Fig. 2 represents a side elevational view;
Fig. 3 represents an end elevational view;
Fig. 4 represents an elevational view taken from the opposite end of Fig. 3, and
Fig. 5 represents a bottom plan view thereof.

I claim:

The ornamental design for a cushion cap for cash register control keys, substantially as shown.

GARRY W. MUNSON,
